UNITED STATES PATENT OFFICE.

ROBERT C. COLE, OF HARTFORD, CONNECTICUT, ASSIGNOR TO THE JOHNS-PRATT COMPANY, OF HARTFORD, CONNECTICUT, A CORPORATION OF CONNECTICUT.

CUT-OUT BOX.

1,135,358.

Specification of Letters Patent.

Patented Apr. 13, 1915.

Application filed March 17, 1914. Serial No. 825,204.

To all whom it may concern:

Be it known that I, ROBERT C. COLE, a citizen of the United States, residing at Hartford, in the county of Hartford and State of Connecticut, have invented a new and useful Improvement in Cut-Out Boxes, of which the following is a specification.

This invention relates to a cut-out box which is more particularly designed for containing a main line switch and fuses, although of course it is adapted to contain other than a main line switch and fuses.

The object of the invention is to provide a cut-out box of this nature which is so constructed that the circuit connections can be sealed therein and the fuses cannot be reached unless the circuit is open.

The embodiment of the invention illustrated consists of a box in which is mounted a block that supports a switch and the fuses. The cover of the box is arranged so that it may be quickly sealed by simple means and it has an opening provided with a shutter which slides back and forth over the fuses. The shutter is arranged to engage with the switch or a portion connected thereto so that when the shutter is moved to expose the fuses the switch will be opened, and when the shutter is moved to close the opening in the cover and conceal the fuses the switch will be closed.

Of the accompanying drawings, Figure 1 shows a plan of a box which embodies the invention, with the cover in place and the shutter closed. Fig. 2 shows an edge view of the same. Fig. 3 shows a plan with the cover removed. Fig. 4 shows a section with the shutter in the cover and also the switch in the box closed. Fig. 5 shows a similar section with the shutter started on its open movement and the switch thrown open.

The box or casing 1 may be of any desired size and shape,—that shown being formed of pressed steel with the usual side openings for the entrance of the conductors. One edge of the box shown is turned over so as to form a flange 2 on the front, and one edge of the cover 3 is passed under this flange. Studs 4 project from near the corners of the cover into the corners of the box. A slot is made in one edge of the cover for receiving the perforated ear 5 through which a common form of seal is passed for securing the cover in place. An opening or window is made in the cover, and arranged

to close this opening is a shutter 6. This shutter is located on the inside of the cover and is held in position by studs 7 which extend through the cover and slots 8 in the shutter. The shutter has a handle 9 by 60 which it may be opened and closed.

In the box is a block 10 of non-conducting material. This block is mounted on a frame 11 that is fastened to the back of the box. In the front face of the block 10 is a pocket 65 12 in which are mounted clips 13 for the connection of fuses 14. The block is located so that this pocket is back of the window in the cover that is closed by the shutter. The fuse clips at one end are electrically connected with terminals 15 to which the ends of the load wires may be attached. The other fuse clips are electrically connected by conductors 16 with the ears 17 between which the switch blades 18 of a common 70 form of knife switch are pivoted. The other end of the switch is adapted to be engaged with and disengaged from the spring contacts 19 that are electrically connected with the terminals 20 to which the other service 80 wires may be connected. The switch is located in a pocket on the back or opposite side of the block from the pocket containing the fuses. The blades 18 of the knife switch are connected by an insulating piece 21 85 from the center of which a knob 22 extends forwardly. Attached to the back of the shutter and projecting rearwardly is a yoke 23 which is arranged to embrace the knob 22 on the block that connects the switch 90 blades.

When the shutter is drawn down so as to close the opening in the cover in front of the fuses, the yoke on its back engages the knob on the switch and causes the switch 95 blades to swing forward and close the circuit. Just as soon as the shutter is started up so as to expose the fuses, the yoke on its back by contact with the knob on the switch, throws the switch blades backward so as to 100 open the circuit. Continuing the opening movement of the shutter swings the switch blades still farther back so that the yoke will pass the knob. The knob projects forwardly into a slot in the insulating block 105 and the yoke extends rearwardly into the same slot. When the shutter is pushed way up, the yoke on its back is carried out of the slot in the insulating block and then the cover can be removed by lifting one edge 110

from the sealing ear and then drawing the other edge out from under the flange on the edge of the box.

This invention provides a cut-out box 5 with a switch and with fuses that can be inclosed and sealed. At any time the switch may be opened and the fuses may be inspected and others substituted if necessary, but whenever the fuses are exposed the circuit is open so that there is no danger to anyone in handling the fuses. The shutter cannot be opened to expose the fuses without opening the circuit, and the cover cannot be removed until the shutter is wide open.

The invention claimed is:

1. The combination with an inclosing case having a cover with a window therein, of a switch mounted in the case, a shutter movable on the cover for opening and closing said window, means on the outside of the cover for moving the shutter, and means so connecting the shutter with the switch that closing the shutter closes the switch and opening the shutter opens the switch.

2. The combination with an inclosing case having a cover with a window therein, of a switch mounted in the case, fuses arranged in the case and electrically connected with the switch, a shutter movable on the cover for opening and closing said window, means on the outside of the cover for moving the shutter, and means so connecting the shutter with the switch that closing the shutter closes the switch and the circuit through the fuses and opening the shutter opens the switch and the circuit through the fuses.

3. The combination with an inclosing case having a cover with a window therein, of an insulating block having fuse terminals on one face, a switch on the other face, electrical connections between the fuse terminals and the switch, a shutter movable on the cover for opening and closing said window, means on the outside of the cover for moving the shutter, and means so connecting the shutter with the switch that closing the shutter closes the switch and opening the shutter opens the switch.

50 4. The combination with an inclosing case having a cover with a window therein, of an insulating block having a pocket in its front face opposite the window in the cover, fuse

terminals arranged in said pocket, a switch on the back face of said block, connections 55 between the fuse terminals and the switch, a shutter adapted to open and close the window in the cover, means on the outside of the cover for moving the shutter, and means so connecting the shutter with the switch 60 that the movement of the former will move the latter.

5. The combination of an inclosing case having a removable cover, said cover having a window with a shutter adapted to open 65 and close said window, means on the outside of the cover for moving the shutter, an insulating block having a slot in one edge mounted in the case, fuse terminals on the front of the block opposite the window, a 70 switch mounted on the back of the block, electrical connections between the fuse terminals and the switch, and means projecting from the shutter through said slot in the block into such engagement with a part of 75 the switch that the movement of the shutter throws the switch and that the cover cannot be removed until after the movement of the shutter has fully opened the switch.

6. The combination with an inclosing case 80 having a window in one side, of an insulating block mounted in the case, a switch mounted on the block and entirely inclosed by the case, fuse terminals mounted on the block opposite said window and electrically 85 connected with the switch, a shutter adapted to be moved for opening and closing the window in the case in front of the fuse terminals, and means connecting the shutter with the switch, said means being the only 90 means for opening and closing the switch.

7. The combination with a casing having a removable cover with a window in the front and a movable shutter adapted to open and close said window, of a switch entirely 95 inclosed within the casing, fuses inclosed within the casing and electrically connected with the switch, and means actuated by the movement of the shutter for opening and closing the switch and for releasing and 100 locking the cover.
